METHOD AND APPARATUS FOR MAKING A METALLIC BELT

Edwin T. Lorig, Pittsburgh, Pa., assignor to United States Steel Corporation, a corporation of New Jersey

Application March 13, 1952, Serial No. 276,301

12 Claims. (Cl. 29—407)

This invention relates to a method and apparatus for making metallic belts and particularly for making such belts from steel strip. At present there is a large demand for light gage flat stainless steel conveyor belts, but it is difficult to secure sufficient straightness of the edges to permit proper operation of the belt over conveyor pulleys. The camber in cold rolled strip is often so great in the total length required for metal belts that if used for a metal belt in the "as rolled" condition, the center line of the belt would move in a lateral arc even when using centering pulleys of the type shown in my copending applications, Serial No. 97,218, filed June 4, 1949, now Patent No. 2,593,157; Serial No. 138,389, filed January 13, 1950, now Patent No. 2,592,581; and Serial No. 145,648 filed February 23, 1950, now Patent No. 2,593,158. For that reason in most instances it is necessary to cut, fit, patch and trim a length or lengths of strip to secure sufficient straightness in the finished belt. This is a tedious and costly procedure and results in the waste of much of the strip.

One method of making metallic belts is disclosed in my copending application, Serial No. 271,404, filed February 13, 1952. That method is suitable when the strip from which the belt is made does not have so much camber that the belt cannot be readily centered on the self-centering pulleys used in such method. However, that method is not suitable in some instances especially when making long belts.

It is therefore an object of my invention to provide a method of making a metallic belt from a length of cold rolled strip regardless of the amount of camber therein.

Another object is to provide apparatus suitable for carrying out this method.

Still another object is to provide apparatus suitable for marking parallel lines on the side edges of a strip.

These and other objects will become more apparent after referring to the following specification and attached drawings, in which:

Figure 1 is a side elevation of the apparatus of my invention;

Figure 2 is an enlarged end view of the apparatus of Figure 1;

Figure 3 is a view taken on the line III—III of Figure 2;

Figure 4 is a sectional view taken on the line IV—IV of Figure 3;

Figure 5 is a sectional view taken on the line V—V of Figure 4; and

Figure 6 is a plan view of the roll shown in Figures 4 and 5.

Referring more particularly to the drawings, reference numeral 2 indicates a self-centering roll or pulley of the type disclosed in my copending Patent No. 2,593,158. As best shown in Figure 2, spaced apart spherical bearings 4 are provided for supporting a shaft 6 which forms part of the roll. The shaft 6 has an extension 8 at one end so that it can be driven from any suitable source of power. As more fully described in my copending

2

Patent No. 2,593,158, pulley 2 is made up of two opposed frusto-conical rolls 10 securely fastened to the shaft 6 with their large diameter ends adjacent each other. A flange 12 is mounted on the adjacent end of each of the rolls 10 and the outer surface of these flanges are also frusto-conical.

A scribing device, indicated generally by the reference numeral 14, is mounted adjacent the pulley 2 on base 16. This scribing device includes a pivot support 18 mounted in the brackets 20. A two-arm lever 22 is pivotally mounted on bearings 24 supported by the member 18. One arm 26 of the lever 22 is arranged on the transverse center line of the pulley 2 as clearly shown in Figure 2 and the other arm 28 is provided with a handle 30. A compression spring 32 extends between the base 16 and arm 28 and normally holds the arm 26 a short distance from the face of pulley 2. The upper end of the arm 26 is provided with an opening 34 for receiving a graduated bar 36 which is held in adjusted position by means of a screw 38. A scribe holder 40 on each end of the bar 36 is held in adjusted position by means of a screw 42. A scribe 44 is mounted in each holder 40 and is held in position by means of a screw 46.

25 A second self-centering pulley 48 is mounted in spaced apart relationship from the pulley 2. The pulley 48 is mounted in spherical bearings 50 and is identical with pulley 2 except that no shaft extension 8 is provided. The bearings 50 are mounted on a base 52 which is provided with graduations 54 at one end thereof. The opposite end of the base 52 is pivotally mounted at 56 on a sub-base 58. The base 52 has two elongated arcuate slots 60 for receiving bolts 62 which extend upwardly through the sub-base 58. The sub-base 58 is provided with a stationary pointer 64. When the pointer 64 is at the zero position of scale 54 the pulleys 2 and 48 will be parallel and in exact alignment. The nuts are then tightened on bolts 62 and the nut 66 is drawn tight so as to hold the roll 48 in this adjusted position. If desired, the entire pulley assembly may be mounted for movement toward and away from the pulley 2 in the manner set forth in my above mentioned copending application, Serial No. 271,404, filed February 13, 1952.

In making a belt a piece of cold rolled strip S is passed around the pulleys 2 and 48 with its ends held together by means of two strip clamps 68, one arranged on each side edge of the strip. The clamps 68 are adjusted so that the vertical distance AB is the same at each edge of the strip when the clamps 68 are spaced midway between pulleys 2 and 48. The strip S is then run back and forth over the pulleys 2 and 48 until it reaches a stabilized position thereon. The movement of the strip S will be limited so that the clamps 68 will not pass on to the pulleys. Holes 70 are then punched or otherwise formed in the strip S and a bar 72, having four slotted openings 74 therein is arranged on the outside of the strip S with the openings 74 over the holes 70. The slotted openings 74 are parallel to each other. U-bolts 76 are then inserted through the holes 70 and the openings 74 and nuts 78 threaded thereon to hold the strip ends together. The scribes 40 are arranged apart a distance equal to the desired width of strip and the handle 30 lifted with the help of spring 32 until the scribes 44 bear against the strip S. The strip is then rotated about the pulleys 2 and 48 until two parallel straight lines are marked thereon. Transversely parallel lines are then scribed on each end of the strip S immediately adjacent the clamp bar 72 and perpendicular to the longitudinal scribe lines. The strip S is then sheared along the longitudinal and transverse scribe lines and its ends fastened together as by welding to form an endless belt.

3

While one embodiment of my invention has been shown and described it will be apparent that other adaptations and modifications may be made without departing from the scope of the following claims.

I claim:

1. Apparatus for marking two parallel lines on a strip comprising a pair of spaced apart automatic centering pulleys around which the strip passes, said pulleys being arranged in substantial parallelism and in alignment with one another, means for rotating one of said pulleys, and two scribes mounted adjacent one of said pulleys in spaced apart relationship across the face of the pulleys, each of said pulleys including a pair of spaced apart outer strip supporting portions, one on each side of the transverse center of the pulley, and means for positively causing one of the strip supporting portions to rotate at the same angular velocity as the other strip supporting surface, each of said strip supporting surfaces being arranged to provide a force urging the strip passing thereover toward the transverse center of the pulley, the total width of the strip supporting portions of at least one of the said pulleys being less than the width of the said strip so that the edges of the strip overhang the strip supporting portions.

2. Apparatus for marking two parallel lines on a strip according to claim 1 including a pivotally mounted two arm lever adjacent one of said pulleys, a bar mounted at the free end of one of said arms and extending across the face of the adjacent pulley, and means for mounting said scribes on said bar one adjacent each end thereof.

3. Apparatus for marking two parallel lines on a strip according to claim 1 including a pivotal mounting for one end of one of said pulleys, and means for moving the other end of said pivotal mounted pulley about said pivotal mounting.

4. Apparatus for marking two parallel lines on a strip according to claim 3 including a pivotally mounted two-arm lever adjacent one of said pulleys, a bar mounted at the free end of one of said arms and extending across the face of the adjacent pulley, and means for mounting said scribes on said bar one adjacent each end thereof.

5. Apparatus for marking two parallel lines on a strip comprising a pair of spaced apart automatic centering pulleys around which the strip passes, said pulleys being arranged in substantial parallelism and in alignment with one another, means for rotating one of said pulleys, two scribes mounted adjacent one of said pulleys in spaced apart relationship across the face of the pulleys, each of said pulleys comprising two opposed rolls supported at their outer ends only, and an outwardly extending flange on the adjacent end of each roll, the combined width of said flanges being substantially less than the width of the strip.

6. Apparatus for marking two parallel lines on a strip according to claim 5 including a pivotally mounted two-arm lever adjacent one of said pulleys, a bar mounted at the free end of one of said arms and extending across the face of the adjacent pulley, and means for mounting said scribes on said bar one adjacent each end thereof.

7. Apparatus for marking two parallel lines on a strip according to claim 5 including a pivotal mounting for one end of one of said pulleys, and means for moving the other end of said pivotal mounted pulley about said pivotal mounting.

8. Apparatus for marking two parallel lines on a strip according to claim 7 including a pivotally mounted two-arm lever adjacent one of said pulleys, a bar mounted at the free end of one of said arms and extending across the face of the adjacent pulley, and means for mounting said scribes on said bar one adjacent each end thereof.

9. The method of marking two parallel lines on a strip comprising passing the strip around a pair of spaced apart horizontally arranged and aligned automatic centering pulleys, at least one of said pulleys having a strip support-

ing surface of less width than the width of the strip so that the edges of the strip overhang the strip supporting portions, fastening the ends of the strip together with the vertical distance between the top and bottom of the strip at one edge being equal to the vertical distance at the other edge in a plane midway between said pulleys, moving said strip around said pulleys until it reaches a stabilized position on said pulleys, continuing rotation of said strip around said pulleys and holding a scribe against said moving strip adjacent each edge as it passes around one of said pulleys.

10. The method of marking two parallel lines on a strip comprising passing the strip around a pair of spaced apart horizontally arranged and aligned automatic centering pulleys, at least one of said pulleys having a strip supporting surface of less width than the width of the strip so that the edges of the strip overhang the strip supporting portions, fastening the ends of the strip together with adjustable clamps on each edge, adjusting said clamps until the vertical distance between the top and bottom of the strip at one edge is equal to the vertical distance at the other edge in a plane midway between said pulleys, moving said strip around said pulleys until it reaches a stabilized position on said pulleys, forming two spaced apart holes in each end of the strip one adjacent each edge, placing a clamping bar over the adjacent ends of the strip and fastening it to said strip by means of bolts passing through said holes and holes in said bar, removing the adjustable clamps, rotating said strip around said pulleys and holding a scribe against said moving strip adjacent each edge as it passes around one of said pulleys.

11. The method of making an endless belt from a length of metal strip which comprises passing the strip around a pair of spaced apart horizontally arranged and aligned automatic centering pulleys, at least one of said pulleys having a strip supporting surface of less width than the width of the strip so that the edges of the strip overhang the strip supporting portions, fastening the ends of the strip together with the vertical distance between the top and bottom of the strip at one edge being equal to the vertical distance at the other edge in a plane midway between said pulleys, moving said strip around said pulleys until it reaches a stabilized position on said pulleys, continuing rotation of said strip around said pulleys, and holding a scribe against said moving strip adjacent each edge as it passes around one of said pulleys to form longitudinal lines thereon, scribing a transverse line adjacent each end of said strip perpendicular to the longitudinal line, cutting the strip along said longitudinal and transverse lines, and fastening the ends of the strip together.

12. The method of making an endless belt from a length of metal strip which comprises passing the strip around a pair of spaced apart horizontally arranged and aligned automatic centering pulleys, at least one of said pulleys having a strip supporting surface of less width than the width of the strip so that the edges of the strip overhang the strip supporting portions, fastening the ends of the strip together with adjustable clamps on each edge, adjusting said clamps until the vertical distance between the top and bottom of the strip at one edge is equal to the vertical distance at the other edge in a plane midway between said pulleys, moving said strip around said pulleys until it reaches a stabilized position on said pulleys, forming two spaced apart holes in each end of the strip one adjacent each edge, placing a clamping bar over the adjacent ends of the strip and fastening it to said strip by means of bolts passing through said holes and holes in said bar, removing the adjustable clamps, rotating said strip around said pulleys and holding a scribe against said moving strip adjacent each edge as it passes around one of said pulleys to form longitudinal lines thereon, scribing a transverse line adjacent each end of said strip perpendicular to the longitudinal line, cutting the strip along said

longitudinal and transverse lines, and fastening the ends of the strip together.
